(57) **CLAIM**

The ornamental design for a mobile phone, as shown and described.

DESCRIPTION

FIG. 1 is a front elevational view of a mobile phone of the claimed design.

FIG. 2 is another front elevational view of the mobile phone of FIG. 1.

FIG. 3 is a rear elevational view of the mobile phone of FIG. 1.

FIG. 4 is a top view of the mobile phone of FIG. 1.

FIG. 5 is a bottom view of the mobile phone of FIG. 1.

FIG. 6 is a right side view of the mobile phone of FIG. 1.

FIG. 7 is a left side view of the mobile phone of FIG. 1; and, FIG. 8 is a perspective view of the mobile phone of FIG. 1. The cord, which extends upward from the top of the mobile phone and forms a loop, has been shown broken away in FIGS. 2-8 for convenience of illustration.
